UNITED STATES PATENT OFFICE.

RUDOLF KERSTEN, OF DRESDEN, NORTH DAKOTA.

STOVEPIPE JOINT OR COUPLING.

1,356,373.

Specification of Letters Patent.

Patented Oct. 19, 1920.

Application filed November 9, 1915. Serial No. 60,520.

To all whom it may concern:

Be it known that I, RUDOLF KERSTEN, a citizen of the United States, residing at Dresden, in the county of Cavalier and State 5 of North Dakota, have invented certain new and useful Improvements in Stovepipe Joints or Couplings, of which the following is a specification.

This invention relates to the class of stoves 10 and furnaces, and more specifically to stovepipe joints or couplings.

The object of my invention is to provide a stove pipe joint or coupling to which from one to three lead pipes may be connected and 15 having a main outlet. The intake branches of the joint are so joined to the main outlet thereof that there will be a direct draft through all of the lead pipes connected with said joint. Acute angles or bends are avoided 20 in my construction, thus eliminating improper draft to the stove or furnace. My invention also contemplates the tight closing of any of the branch intake pipes not in actual use, whereby the entire draft is received 25 by the branch or branches being used.

Other objects of this invention not at this time more particularly enumerated, will be clearly understood from the detailed description and drawings forming a part of 30 this specification.

Furthermore, this invention consists in the novel arrangement and combination of parts more particularly described in the following specification and embodied in the 35 claim appended hereunto and forming a part of this application.

The figure of the drawing is a front elevation of my stove pipe joint or coupling.

Referring further to the drawing, 1 designates the body portion of my joint, from 40 which a main outlet pipe 2 projects, while oblique branch inlet pipes 3 and 4 are formed integrally with said body portion and are of substantially the same diameter as 45 2 and are oppositely disposed with respect to said main outlet pipe 2, and at an oblique angle thereto. An inlet branch 5 is secured to said body portion within the crotch formed by the obliquely disposed branches 50 3 and 4, said branch 5 being in alinement with the main outlet 2 and of approximately the same diameter.

Furthermore, the angle of entry of the 55 pipes 3, 4 and 5 is of such a degree that lines drawn from the internal sides of the pipes 3 and 4 and through the medial axis of the

pipe 5 will intersect at a point equidistant from the exterior sides of the body 1, at the point where the said body 1 is of a diameter equivalent to the combined diameters of the 60 pipes 3 and 4 and also, lines drawn through the medial axes of each of the pipes 3, 4 and 5 will intersect on the medial axis of the pipe 2 at the point where it enters the body 1. By this construction it will be clear to persons skilled in the art to which this invention applies, that a complete scavenging of the body 1 will be effected on account of the great improvements in the draft there- 65 through. It being pointed out that the 70 greatest combination of air currents will be at the point of intersection of the pipe with the body 1, while the first actual combining of the draft of the air currents from the pipes 3, 4 and 5 will be at the point where the me- 75 dian axis of the branch 5 and lines drawn from the interior sides of the branches 3 and 4 intersect as heretofore mentioned.

The utility, adaptability, and advantages of my improved form of stove pipe joint or 80 coupling being obvious, it is unnecessary to further enlarge upon the same herein.

Having now described and pointed out the new and useful features of my invention, I do not limit myself to the shape of certain 85 parts where the shape is not essential, nor do I restrict myself to the exact details of construction shown and described, but mean and intend to claim all equivalents and variations thereof, not departing in principle 90 from my invention, and falling within the purview of the appended claim.

What I claim as my invention and desire to secure by Letters Patent is:

A pipe joint consisting of a body portion, 95 an outlet pipe formed on the body portion, obliquely disposed inlet pipes formed integrally with the body portion, an inlet pipe connected with the body portion between the oblique inlet pipes and communicating 100 with the body portion for intersection with the oblique inlet pipes at a point substantially one-third of their length, the extremities of the oblique inlet pipes being bent to extend substantially parallel with the intermediate inlet pipe, and the walls of the body portion being slightly indented to form a continuation of the curvature of the walls 105 of the inlet pipes.

In testimony whereof I affix my signature 110 hereto.

RUDOLF KERSTEN.
